CLAIM

The ornamental design for a railing plant pot holder, as shown and described.

DESCRIPTION

FIG. 1 is a perspective view of a first embodiment of a railing plant pot holder showing my new design, the broken line disclosure of the iron railing on which it is positioned is for illustrative purposes only and forms no part of the claimed design.

FIG. 2 is a perspective view of a second embodiment thereof.

FIG. 3 is a perspective view of a third embodiment thereof; and,

FIG. 4 is a perspective view of a fourth embodiment thereof, the broken line disclosure of the 2"×4" board railing on which it is positioned is for illustrative purposes only and forms no part of the claimed design.
